FOREIGN PATENT DOCUMENTS

JP 005115037-0009 * 3/2018

Primary Examiner — Paula Allen Greene

(74) Attorney, Agent, or Firm — Amin, Turocy & Watson,
LLP(57) **CLAIM**

The ornamental design for an earphone, as shown and described.

DESCRIPTION

FIG. 1 is a front, top and left-side perspective view of an earphone showing my new design;

FIG. 2 is a rear, top and left-side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right-side elevational view thereof; and,

FIG. 8 is a left-side elevational view thereof.

The broken lines of the drawings represent portions of the earphone that are not part of the claimed design.
